MOP WRINGER

William Trostler, Cleveland Heights, Ohio

Application September 5, 1945, Serial No. 614,532

8 Claims. (Cl. 15—262)

1

This invention relates generally to mop wringers, but has reference more particularly to the type of portable mop wringer which is adapted to be supported on a bucket into which the water from the mop is to be wrung.

A primary object of the invention is to provide a mop wringer of the type described, having improved means for facilitating the mop-wringing operation.

Another object of the invention is to provide a mop wringer of the character described, having means incorporated therein for supporting the movable roll in rolling contact with a base member during the initial phase of the mop-wringing operation.

A further object of the invention is to provide a mop wringer of the character described, having means incorporated therein for elevating the movable roll out of rolling contact with the base member during the mop-wringing operation, whereby to facilitate rotation of said roll during the mop-wringing operation.

A further object of the invention is to provide a mop wringer of the character described, which consists of a minimum number of parts which are inexpensive to manufacture, and which can be easily and quickly assembled at low cost.

A still further object of the invention is to provide a mop wringer of the character described, having manually-controlled rack and gear means for augmenting the rotation of the movable roll during the mop-wringing operation.

Other objects and advantages of the invention will be apparent during the course of the following description.

In the accompanying drawings, forming a part of this specification, and in which like numerals are employed to designate like parts throughout the same,

Fig. 1 is a top plan view of a mop wringer made in accordance with the invention;

Fig. 2 is a cross-sectional view, taken on the line 2—2 of Fig. 1, and showing the movable wringer roll in retracted or inoperative position;

Fig. 3 is a view similar to Fig. 2, but showing the movable wringer roll in advanced or operative position;

Fig. 4 is a view similar to Fig. 3, but showing a modification of the wringer, and

Fig. 5 is a fragmentary cross-sectional view, taken on the line 5—5 of Fig. 4.

Referring more particularly to Figs. 1 to 3 inclusive of the drawings, it will be seen that a mop

2

wringing constructed in accordance with the invention comprises a base or frame which is preferably formed from a single length of angle iron bent to a more or less rectangular form to provide sides 1 and 2, and ends 3 and 4, the ends of said length of angle iron being connected, as by rivets 5, to a clip 6, having a downwardly extending flange 7.

The horizontal legs of the aforesaid sides and ends of the base or frame are disposed in a common horizontal plane, thereby facilitating placement of the mop wringer on the upper edge of a bucket or pail B, which is indicated by dotted lines in the drawings. To prevent lateral displacement of the mop wringer from the bucket, I provide a second clip 8, which is secured, as by rivets 9, to the ends of the angle iron base, in parallel spaced relation to the flange 7 of the clip 6. By disposing the flange 7 inside the bucket, and the clip 8 outside the bucket, as clearly shown in Figs. 2 and 3, the mop wringer is firmly secured against lateral displacement. The clips 6 and 8 thus serve a double purpose in that they secure together the ends of the angle iron length to complete the base, and at the same time, provide a means for retaining such base on the bucket.

Secured, as by rivets 10, to the vertical legs of the sides 1 and 2 adjacent the end 4, are brackets or plates 11, portions of which extend above such vertical legs to provide bearings for the trunnions 12 of a stationary wringer roll 13, this roll, it being noted, being disposed sufficiently above the horizontal legs of the sides 1 and 2 to be freely rotatable at all times.

Pivotedly secured, as by rivets 14, to the vertical legs of the sides 1 and 2 adjacent the end 3 of the base, is a foot plate or member 15, of rectangular form, having downturned flanges 16 and 17 at the front and rear respectively, and downturned flanges 18 and 19 at its sides.

Pivotedly secured, as by rivets 20, to the flanges 18 and 19, adjacent the flange 16, are curved members 21, which are interconnected, intermediate their ends, by a rod 22, so that the members 21 are movable as a unit. The lower ends of the members 21 provide bearings for the trunnions 23 of a movable roll 24, which is similar in length and diameter, to the roll 13.

A tension coil spring 25 interconnects the central portion of the rod 22 with the central portion of the flange 17 of the foot plate 15.

The members 21 are also provided with cam portions 26, the function of which will be presently described.

The members 21 are normally maintained in the position shown in Figs. 1 and 2 by means of the spring 25, and this position of the members 21 results in maintenance of the foot plate 15 in the position shown in these figures. It will be noted that when the members 21 are in this position, the roll 24 bears directly on the horizontal legs of the base ends 1 and 2, which legs thus serve as tracks or guides for the roll 24. It will be further noted that when the roll 24 thus bears directly on such legs, the cam surfaces or portions 26 of the members 21 are elevated slightly above such legs, as is clearly apparent in Fig. 2.

When it is desired to wring a mop, which is diagrammatically indicated by reference character M in Fig. 3, the mop is placed in the bucket B, and the operator then steps on the foot plate 15, exerting pressure upon the foot plate until the roll 24 is moved to the mop-wringing position shown in Fig. 3, after which the operator pulls the mop upwardly through the rolls 13 and 24, thereby wringing the mop.

It will be noted that in the initial stages of the aforesaid movement, the roll 24 rolls on the horizontal legs of the sides 1 and 2 of the base, so that the movement of the roll to its operative position is greatly facilitated. If the roll 24 remained in contact with the base while in the operative position shown in Fig. 3, the movement of the mop M would be hampered, due to the frictional engagement of the roll 24 with such base, which would resist turning of this roll. As the roll 24 approaches its operative position, however, the cam portions 26 of the member 21 come into engagement with the horizontal legs of the sides 1 and 2, as shown in Fig. 3, thereby elevating the roll 24 above such legs. This permits the roll 24 to rotate freely in its bearings, and, as a result, the wringing of the mop is greatly facilitated. The provision of the cam portions 26 on the members 21 is therefore a highly important feature of the invention.

It will be further noted that the foot plate 15 and the members 21 form elements of a toggle, which enable a relatively small pressure applied to the foot plate to be converted into a fairly high pressure of the roll 24 against the mop.

After the mop has been wrung, the foot is removed from the plate 15, and the contraction of the spring 25 then automatically restores the movable parts to the position shown in Figs. 1 and 2.

In cases where mops of relatively large size are to be wrung, such for example as mops designed for use in hotels and office buildings, it is desirable, although not absolutely necessary, to provide means for augmenting the pull on the mop while being wrung. Such means is illustrated in Figs. 4 and 5.

Referring to Figs. 4 and 5, it will be seen that the trunnion 12' at one end of the roll 13 is extended beyond the side 1 of the base to provide a support for a pinion 27, which is keyed or otherwise rigidly secured to the trunnion, so as to be rotatable with the roll 13, the pinion being maintained against axial displacement from the trunnion by means of a collar 28 and a cotter pin 29.

Welded, or otherwise secured to the side 1 of the base is a track member or guide 30 for a reciprocal rack 31, which is in mesh with the pinion 27, the rack being provided at its upper end with a grip or handle 32.

In the use of the aforesaid means, as the mop

in one hand, and the handle 32 of the rack 31 in the other hand, and as the mop is pulled upwardly, the handle 32 is also pulled upwardly, thereby causing the rack to rotate the pinion 27, which, in turn, causes the roll 13 to be rotated, thereby facilitating the wringing of the mop.

It is to be understood that the forms of my invention herewith shown and described, are to be taken as preferred examples of the same, and that various changes in the shape, size and arrangement of parts may be resorted to, without departing from the spirit of my invention, or the scope of the subjoined claims.

Having thus described my invention, I claim:

1. In a mop wringer, a base member, a stationary roll on said base member, a movable roll on said base member movable into coaction with said stationary roll, said movable roll being normally supported in rolling contact with said base member, and means carried by said base member responsive to movement of said movable roll toward said stationary roll for elevating the movable roll out of rolling contact with said base member.

2. A mop wringer, as defined in claim 1, in which said means comprises a pair of roll-supporting links having cam portions movable into engagement with said base member.

3. In a mop wringer, a base member, a stationary roll on said base member, a movable roll on said base member, and means on said base member for moving said movable roll into position for coaction with said stationary roll, said means comprising a foot plate disposed at an angle to said base member and pivotally secured thereto, a pair of members pivotally secured to said foot plate and having portions forming bearings for said movable roll, and spring means interconnecting said foot plate and last-named members, and operative to withdraw the movable roll from said position upon release of pressure upon said foot plate.

4. In a mop wringer, a base member, a stationary roll on said base member, a movable roll on said base member, and means on said base member for moving said movable roll into position for coaction with said stationary roll, said means comprising a foot plate disposed at an angle to said base member and pivotally secured thereto, a pair of members pivotally secured to said foot plate and having portions forming bearings for said movable roll, spring means interconnecting said foot plate and said pair of members for normally maintaining said movable roll in a position in which the movable roll has rolling contact with said base member, and means on said pair of members operative during the course of movement of the movable roll to its coacting position to move said movable roll out of rolling contact with said base member.

5. A mop wringer as defined in claim 4, in which said last-named means comprises cam portions on said pair of members.

6. In a mop wringer, a base member, a stationary roll on said base member, a movable roll on said base member, means on said base member for moving said movable roll into position for coaction with said stationary roll, said means comprising a foot plate disposed at an angle to said base member and pivotally secured thereto, a pair of spaced members pivotally secured to said foot plate and having portions forming bearings for said movable roll, a rod interconnecting said pair of members, and spring means interconnecting said foot plate and rod, and operative to with-

draw the movable roll from said position upon release of pressure upon said foot plate.

7. In a mop wringer, a base member, a rotatable stationary roll on said base member, a movable roll on said base member movable into coaction with said stationary roll for mop-wringing purposes, and manually-operated means interconnecting said base member and said stationary roll for facilitating the rotation of the stationary roll during a mop-wringing operation.

8. In a mop wringer, a base member, a rotatable stationary roll on said base member, a movable roll on said base member movable into coaction with said stationary roll for mop-wringing purposes, and means interconnecting said base member and said stationary roll for rotating said stationary roll during a mop wringing operation, said means comprising a pinion carried by said

stationary roll, and a manually-controlled rack on said base member in mesh with said pinion.
